UNITED STATES PATENT OFFICE.

HALLIE E. TURNER, OF BEAUMONT, TEXAS.

WHIPSTOCK.

Application filed February 3, 1928. Serial No. 251,543.

My invention relates to whipstocks to be employed in well drilling operations to change the course of the well bore when, for some reason, the bottom of the well has been 5 filled with tools, pipe or other material, making it impossible for the drill to proceed. These tools or pipe which may be accidentally left in the bottom of the well are usually termed "junk" and when the well has been 10 thus junked, a whipstock is employed to divert a milling cutter or other similar tool through the side of the casing and past the junk so that the hole may be continued downwardly without the necessity of milling 15 up the metal at the bottom of the hole. The usual difficulties encountered in the use of ordinary whipstock are that the head of the whipstock will not remain stationary but is liable to rotate with the milling cutter 20 when the attempt is made to sidetrack the drill by cutting through the wall of the casing. A hole may be started through the wall of the casing by deflection of the cutter when it contacts with the sloping face of 25 the whipstock, but the whipstock may rotate so as to swing the milling cutter around at a different angle so that the opening which is started at one side of the casing will be closed by the whipstock and a new one 30 started; it being impossible to prevent the whipstock from rotation.

It is an object of my invention to provide a whipstock for use in sidetracking operations, which will not turn or change its position in the well after it has once been set 35 for operation.

It is desired to provide a whipstock which is adaptable for casings of different sizes and which may be easily placed in position 40 for operation.

Referring to the drawing herewith, Fig. 1 is a side elevation of a whipstock embodying my invention shown in a casing, said casing being in longitudinal section. Fig. 45 2 is a similar view, illustrating the tool in "set" position. Fig. 3 is a transverse section on the plane 3-3 of Fig. 1. Fig. 4 is a transverse section on the plane 4-4 of Fig. 1. Like numerals are employed to designate 50 like parts in all the views.

The body of my whipstock is of solid metal, such as steel, and comprises a head 1 of an outline generally cylindrical to fit within a well casing 2. One side of the 55 body is tapered toward the upper end por-

tion at 3 and this tapered surface is recessed or concaved, as shown at 4 in Fig. 4, to serve as a guide for a cutting head such as a milling cutter and will act to force it against the side of the casing. This concaved surface extends from the upper end downwardly along the beveled face for the full length of the bevel. A morticed groove 6 is formed centrally of the concaved surface from a point 7 therein, downwardly to the 65 end of the taper.

A wedge-shaped dog 8 fits within the seat 4 toward the lower end thereof. Its upper end comes to an edge at 5. It has a tongue or key 10 thereon fitting slidably within the 70 groove 6 to hold said dog in position in the seat 4. The outer surface of the dog is rounded to conform to the cylindrical contour of the head 1 and is grooved longitudinally to provide teeth 11 adapted to grip 75 the casing. The upper end, 5, of the dog fits within the seat 4 and is beveled at 12 and concaved to continue the guide groove 4 of the head but at a more abrupt taper.

I may provide a shear pin 13 of frangible 80 material extending through the lower end of the dog and into the head so as to hold the dog temporarily in inoperative position.

The head 1 may be mounted upon a length of pipe or rod 14 so as to space the head at 85 the proper distance from the bottom of the well.

In use, the tool, mounted as shown in Fig. 1, and without the shear pin 13, may be dropped from the upper end of the casing 90 downwardly to the bottom. The dog may move upwardly until the key 10 reaches the shoulder 7, and will not interfere with the setting of the tool near the bottom, and at the desired level in the well. As the pipe 95 14 at the lower end of the whipstock hits the bottom of the well, the jar will force the dog 8 downwardly to wedge between the head and the casing so that the teeth 11 will seize into the casing and tend to hold the 100 whipstock firmly against rotation. As may be noted from Fig. 3, the side of the head opposite the dog is forced against the casing and the parts will be so securely wedged to the casing that no rotation of the tool in 105 the casing is possible. It is also an advantage that the upper edge of the whipstock is held by the wedge firmly against the casing so that there is no chance for the milling tool to get hung up on the said upper edge 110.

as now sometimes happens with the old type of whipstock.

When it is desired to set the whipstock with a setting tool, as is sometimes done, the setting tool may be connected releasably to the whipstock at the opening 15 there provided. The shear pin will be employed to secure the wedge to the head while the tool is being properly located at the bottom 10 of the well. The setting tool may be then released and a blow may be struck with the setting tool upon the dog to release it from the shear pin 13, and drive it into locking position.

15 When the whipstock is thus set, a milling tool may be lowered into contact with the whipstock and rotated to cut an opening in the side of the casing in the usual manner, to allow passage for the well drill to one side 20 of the junk in the bottom of the hole. The concaved guide surface 4 will hold the milling cutter properly centered so that a true and clean hole will be cut in the casing, and there is no danger of the rotation of the 25 whipstock to change the position of the opening being cut. I will therefore be assured of a clean cut hole without difficulty.

What I claim as new is:

1. A whipstock comprising a lower head portion adapted to fit within a well casing, an upper portion beveled on one side to form an elongated taper thereon and a wedge-shaped dog on the lower end of said taper, adapted to move downwardly and wedge 35 said head within said well casing.

2. A whipstock comprising a lower head portion adapted to fit within a well casing, an upper portion beveled on one side to form an elongated taper thereon and a wedge-shaped dog on the lower end of said taper adapted to move downwardly and wedge 40 said head within said well casing, and teeth on the outer surface of said dog to engage said casing.

45 3. A whipstock comprising a lower head portion adapted to fit within a well casing, an upper portion beveled on one side to form an elongated taper thereon and a

wedge-shaped dog on the lower end of said taper adapted to move downwardly and 50 wedge said head within said well casing, said dog having a tongue and groove connection with said tapered portion to prevent relative rotation of said dog and said portion.

4. A whipstock comprising a lower head portion shaped to fit within a well casing, an upper portion having an elongated beveled surface on one side, said surface being concaved, a wedge-shaped dog on said beveled surface adjacent the lower end thereof, 55 means to connect said dog slidably to said head, and means to limit the upward movement of said dog on said upper portion.

5. A whipstock comprising a lower head portion shaped to fit within a well casing, 65 an upper portion having an elongated beveled surface on one side, said surface being concaved, a wedge-shaped dog on said beveled surface adjacent the lower end thereof, means to connect said dog slidably 70 to said upper portion, means to limit the upward movement of said dog on said upper portion; and teeth on said dog cut longitudinally upon its outer face to engage said casing. 75

6. A whipstock body including a lower solid circular head portion, an upper non-circular elongated tapered portion merging with said head portion, and a dog slidably mounted upon the non-circular portion, said 80 dog and said non-circular portions co-acting to form a complete circle.

7. A whipstock body including a lower solid circular head portion, an upper non-circular elongated tapered portion merging with said head portion, and a dog slidably mounted upon the non-circular portion, said 85 dog and said non-circular portions co-acting to form a complete circle, said dog comprising an upper tapered bit engageable surface and a lower vertically grooved casing 90 surface.

In testimony whereof I hereunto affix my signature this 27th day of January, A. D. 1928.

HALLIE E. TURNER.
